UNITED STATES PATENT OFFICE.

WILLIAM B. DAY, OF RICHMOND, KENTUCKY, ASSIGNOR OF ONE-FOURTH TO KELLY B. DAY AND ONE-FOURTH TO H. PHELPS RENICK, BOTH OF WINCHESTER, KENTUCKY.

ANTIFREEZING SYSTEM FOR AUTOMOBILE-RADIATORS.

1,325,558.

Specification of Letters Patent.

Patented Dec. 23, 1919.

Application filed July 10, 1918. Serial No. 244,306.

To all whom it may concern:

Be it known that I, WILLIAM B. DAY, a citizen of the United States, residing at Richmond, in the county of Madison and 5 State of Kentucky, have invented a new and useful Antifreezing System for Automobile-Radiators, of which the following is a specification.

This invention relates to an anti-freezing 10 system for automobile radiators, one of its objects being to provide a tank for receiving the water from the radiator when the automobile is left standing in freezing weather, means being provided whereby, when the engine is set in motion, the water will be elevated 15 from the tank and directed back into the radiator and permitted to circulate in the usual manner.

Another object is to provide a system of 20 this character which can be installed readily and will be inconspicuous.

With the foregoing and other objects in view which will appear as the description proceeds, the invention consists of certain 25 novel details of construction and combinations of parts which will be hereinafter more fully described and pointed out in the claims, it being understood that various changes may be made in the construction 30 of the parts without departing from the spirit or sacrificing any of the advantages of the invention as set forth in the appended claims.

In the accompanying drawings the preferred forms of the invention have been 35 shown.

In said drawings—

Figure 1 is a side elevation of the system 40 constituting the present invention. Fig. 2 is a view showing partly in diagram and partly in section the valve and its connections.

Fig. 3 is a view partly in section and 45 partly in elevation of a modified form of the invention.

Referring to the figures by characters of reference, 1 designates the radiator and 2 the motor of an automobile. Extending 50 downwardly from the bottom of the radiator is a pipe 3 which opens into a valve casing 4. A valve 5 is mounted for rotation in the casing and has a straight passage 6 extending therethrough and another passage 7 therein, the two passages being side by side 55 but out of communication with each other and the passage 7 being so extended as to open through the periphery of the valve at points ninety degrees apart. When the passage 6 is in register with the pipe 3 it also communicates with a port 8 in the casing 60 4, there being a pipe 9 leading from this port to a tank 10 which can be suspended at any desired point but necessarily lower than the bottom of the radiator. While the passage 6 is in position thus to establish communication between the pipes 3 and 9, the passage 7 is in register with two ports 11 and 12 in the casing 4. A pipe leads from the intake manifold of the engine 2 to the port 12 and has been shown at 13. Another 65 pipe 14 leads from the port 11 to the top of the radiator 1 and constitutes an overflow pipe.

The valve can be rotated in any manner desired, as by means of a rod 15, one end of the rod being connected to an arm extending radially from one end of the valve while the other end of the rod is connected to a foot plate, knob, or the like, shown at 16. The arm of the valve has been shown at 17. 70 75 80

The valve casing 4 has a vent opening 18 spaced ninety degrees from the port 11. It is to be understood that the top of the radiator is to be sealed.

Under ordinary conditions the valve 5 is 85 turned so that the passage 7 connects the ports 11 and 19, said valve closing the connection between the pipes 3 and 9. When it is designed to leave the automobile standing where the water in the radiator is likely 90 to freeze, the valve 5 is turned through ninety degrees. This will place the ports 11 and 12 in communication through the passage 7 and will also place the pipes 3 and 9 in communication, as shown in Fig. 2. The 95 tank 10 has had the air previously withdrawn therefrom as hereinafter described and, consequently, as soon as the valve is turned to the position shown in Fig. 2, the water in the radiator will drain into the 100 tank 10. By making the tank with double walls spaced apart in the same manner as a thermos container, the water will not freeze within the tank. When the automobile is to be used and it is desired to start 105 the circulation of the water through the radiator, the valve 5 is left in the position shown in Fig. 2 and the engine is started. This will cause a suction to be set up through the pipes 13 and 14 and as air is withdrawn 110

from the top of the radiator, water will be drawn into the bottom of the radiator through the pipes 9 and 3. As soon as the radiator has been filled the valve is shifted 5 to its first described position with the ports 11 and 19 in communication and the pipe 3 closed. This will leave a partial vacuum within the tank 10.

Instead of utilizing the suction of the 10 engine as the means for controlling the flow of the water to the radiator, a modified system, such as shown in Fig. 3 may be employed. In this system the radiator 20 has a pipe 21 extending from the bottom 15 thereof to a pump 22 driven by the motor and the tank 23 is connected to the pump by a pipe 24. The pump is of the usual type for setting up a forced circulation. Another pipe 25 connects the top of the tank 20 20 with the lower portion of the jacket of the engine and this pipe 25 has a branch 26 leading to the dash 27 where it is provided with an air valve 28.

Under ordinary conditions the tank 23 is 25 filled with air and the water will not circulate therethrough but will flow as ordinarily through the cooling system. When it is desired to withdraw the water from the radiator and jacket, however, the air valve 28 is 30 opened and the air will thus escape from the tank and permit the water to gravitate to the tank. By opening the top of the radiator and operating the pump 21 the water

will be elevated from the tank 23 and a partial vacuum thus established in the tank. 35 The water will then circulate as ordinarily. It is to be understood, of course, that the valve 28 is to be closed while the water is being elevated from the tank.

What is claimed is:—

1. The combination with the motor and radiator of a motor vehicle, of a tank below the level of the radiator, means for elevating water from the tank and forcing it into the radiator thereby to create a partial 45 vacuum in the tank, a pipe connection between the radiator and tank and including a pump, and means for controlling communication between the radiator and tank.

2. The combination with the radiator of 50 a motor vehicle, of a tank, a motor, a valve, and means for shifting the valve to one position to admit air to the top of the radiator and close communication between the radiator and tank, and to another position to open 55 communication between the radiator and the tank and connect the top of the radiator to the intake manifold of the motor.

In testimony that I claim the foregoing as my own, I have hereto affixed my signature 60 in the presence of two witnesses.

WILLIAM B. DAY.
